Attorney,

UNITED STATES PATENT OFFICE

HORACE F. GRUMAN, OF ST. LOUIS, MISSOURI, ASSIGNOR TO LEWIS INVISIBLE STITCH MACHINE COMPANY, OF KITTERY, MAINE, A CORPORATION OF MAINE

SEWING MACHINE

Application filed December 9, 1927. Serial No. 238,793.

This invention relates to new and useful improvements in sewing machines generally, although more particularly to sewing machines for joining two body fabrics by a French seam.

Heretofore, in joining two body fabrics by a French seam, two separate operations on a single needle machine have been required. Two fabrics were first superposed 10 one on the other with their edges in registry and these fabrics were then seamed along a line parallel with the superposed edges by a single needle machine. One of the fabrics was then turned around the previously 15 formed seam and positioned under and against the other fabric in flat relation, to thereby enclose the first formed seam, the marginal portions of the fabrics being positioned between the flat body fabrics. The 20 fabrics were then seamed by a second line of stitches which were located in parallelism with the first line of stitches and which preferably did not penetrate the marginal portions of the fabrics. It quite frequently 25 happened that the edges of the marginal portions projected beyond the second line of stitches and this condition rendered the same bulky and also unsightly.

Among the several objects of my invention are to provide a sewing machine by 30 means of which two body fabrics may be joined by a French seam during a single operation of the machine; to provide means for trimming the marginal portions of the 35 fabrics prior to the formation of the second line of stitches whereby the marginal portions in the completed seam will be completely hidden from view and the same will be less bulky than heretofore, and to provide such a machine which is simple in 40 construction and in operation and which will greatly reduce the cost of operation.

With these and other objects in view which will more fully appear, the nature of the 45 invention will be more clearly understood by following the description, the appended claims, and the several views illustrated in the accompanying drawings.

In the drawings:—
50 Figure 1 is an end view of a flat bed ma-

chine, partly in section, embodying my invention,

Figure 2 is a front elevation of the left hand end of the machine,

Figure 3 is a plan view of the front stitch forming mechanism and cooperating work presenting mechanism, and the trimming mechanism,

Figure 4 is a plan view of the rear stitch forming mechanism and cooperating work presenting mechanism,

Figure 5 is a rear view of the guide plate and associated parts,

Figure 6 is a cross section taken on the line 6—6 of Figure 5,

Figure 7 is a perspective view of the front stitch forming mechanism, the front work presenting mechanism, the trimming mechanism, and the rear stitch forming mechanism and the rear work presenting mechanism,

Figure 8 is a perspective view showing the fabrics and mechanisms in cooperative relation for joining the fabrics by a French seam,

Figure 9 is a perspective view of the French seam produced by my invention,

Figure 10 is a sectional view showing more or less diagrammatically the step of forming the first seam,

Figure 11 is a sectional view showing more or less diagrammatically the step of trimming the downturned marginal portions of the fabrics,

Figure 12 is a sectional view showing more or less diagrammatically the step of forming the ridge of the seamed and trimmed fabrics preparatory to forming the second seam,

Figure 13 is a sectional view showing more or less diagrammatically the step of forming the second seam, and

Figure 14 is a perspective view of a modified form of my invention.

Like reference numerals designate corresponding parts throughout the several figures of the drawings.

My sewing machine is of the flat bed type and includes a base 5 from which projects the usual standard (not shown), and which standard supports an overhanging arm 6 100

having a stitching head 7 supported at its free end. Mounted on the base 5 and extending under the stitching head 7 is a horizontal work support 8.

Disposed below the work support and operating entirely below the same, is the first seam forming mechanism and trimming mechanism, and disposed above the work support in rear of the first seam forming mechanism, is the second or final seam forming mechanism.

The first seam forming mechanism

This first seam forming mechanism includes a stitch forming mechanism and a cooperating work presenting mechanism.

The stitch forming mechanism includes a straight needle 9 which is reciprocatory in a horizontal plane across the line of feed, and a cooperating 4-motion threaded looper 10 for forming a line of Grover and Baker stitches. The needle 9 is attached to a needle bar 11 which is reciprocable in guides 12, 12 mounted on the base 5 and is actuated from the main shaft 13 which is journaled in the overhanging arm 6 by suitable means, not shown. The looper 10 has its loop taking movement in a direction towards the operator or in a direction opposite the direction of feed, and passes above the needle during said movement. The looper is then moved downwardly for one of its needle-avoiding movements, then backwardly for its needle-loop shedding movement, and then upwardly for its other needle-avoiding movement. The looper 10 is attached to a holder 14 which is slidably mounted in a tubular carrier 15. The carrier is pivoted at its lower end to swing in a plane parallel with the line of feed to impart the forward and backward movements to the looper, and the looper holder is reciprocated vertically within the carrier to impart the needle-avoiding movements to the looper. The carrier 15 is oscillated from a rotary shaft 16 journaled in bearings on the base 5 by connections indicated generally at 17, and the looper holder 14 is reciprocated in the carrier from the shaft 16 by connections indicated generally at 18. This looper mechanism per se is shown and described in my Patent 1,750,041, Mar. 11, 1930, and further detail description thereof is believed to be unnecessary.

The work presenting mechanism includes a vertical needle plate or guide 19, a vertical 4-motion feed dog 20 which operates through an opening in the plate 19, and a vertical presser foot 21 which cooperates with the plate 19 and dog 20. The needle 9 reciprocates through alined openings formed in the needle plate 19 and presser foot 21. The feed dog is given backward and forward movements in a plane parallel to the line of feed and lateral movements in a plane at right angles to the line of feed. The feed dog 20 is

connected to an oscillatory feed bar 22 by screws 23, 23 which pass through slots in the dog and engage the feed bar, and thereby permit lateral adjustment of the feed dog. The feed bar 22 is pivoted as at 23^a to a plate 24 which is slidable backwardly and forwardly between guides 24^a, 24^a mounted on the upper end of a post 25 fixed to the base 5. Carried by the feed bar 22 is a roller 26 which cooperates with a cam groove 27 of a cam 28 to oscillate the feed bar laterally. The slidable plate 24 is reciprocated from the shaft 16 through the medium of a link 28^a which is pivotally connected at one end as at 29 to the plate 24 and is pivotally connected at its other end as at 30 to a feed rocker 31 which is pivoted on the base 5 and is oscillated back and forth through the medium of an eccentric strap 32 which cooperates with an eccentric fixed to the shaft 16.

The vertical presser foot 21 is mounted on the upper end of a vertical bracket or arm 33 which is fixed to a sleeve 34 slidable along a horizontal rod 35 mounted in the guides 12, 12. A collar 36 is fixed to the rod 35 beyond the sleeve 34 and a coil spring 37 which is disposed around the sleeve between the arm 33 and the collar 36, functions to yieldingly urge the foot 21 towards the needle plate 19 and feed dog 20. In order to retain the arm 24 against swinging about the rod 35, a guide rod 37^a has one end fixed to the arm and the other end slidable in an opening formed in a lug 38 fixed to the collar 36.

From the foregoing, it will be apparent that in forming the first seam, two body fabrics A and B are positioned on the work support 8 with their marginal edge portions *a* and *b* turned downwardly into side by side relation as shown in Figures 8 and 10. These marginal portions are disposed between the vertical guide plate 19 and the vertical feed dog 20, and the vertical presser foot 21. The feed dog 20 cooperates with the presser foot 21 to feed the marginal portions *a* and *b* of the fabrics past the needle 9 so as to join said portions by a line of stitches *c*. It will be observed that the entire stitch forming mechanism and the entire work presenting mechanism are disposed below the general plane of the body fabrics.

The trimming mechanism

Cooperating with the lower face of the needle plate 19 is a trimmer blade 39 which oscillates in a horizontal plane below the line of stitches *c* to trim the edges of the down-turned marginal portions *a* and *b* of the body fabrics. The blade 39 is detachably secured to a horizontal arm 40 fixed to the upper end of a vertically disposed rock shaft 41 which is journaled in a bracket 42 fixed to the base 5. The rock shaft 41 is oscillated from the shaft 16 by a connection rod 41^a and other connections which are not shown.

Also fixed to the rock shaft 41 is an arm 43 which engages the bracket arm 33 of the presser foot 21 and thereby moves the foot away from the needle plate 19 during the retractile movement of the trimmer blade 39 and during the feeding stroke of the feed dog 20.

The second seam forming mechanism

10 The second seam forming mechanism is disposed in rear of the first seam forming mechanism and includes an upper stitch forming mechanism which is entirely disposed above the general plane of the body fabrics, and a cooperating upper work presenting mechanism.

Disposed in rear of the first seam forming mechanism as well as in rear of the trimming mechanism, is a device for projecting upwardly a ridge *d* of the seamed fabrics into position for seaming by the upper stitch forming mechanism. For this purpose, a stationary ridge forming finger 44 is suitably supported on the base 5, and has its upper 20 end rounded and projecting above the plane of the work support 8 into a ridge-receiving groove 45 formed in the underside of a horizontal plate 46 rigidly secured to the stitching head 7, the groove extending in the line 25 of feed and being disposed in alinement with the marginal edge portions *a* and *b*. The walls of the groove cooperate with the finger 44 to form the ridge *d* in the fabrics during the feeding thereof from the lower or front 30 stitch forming mechanism to the upper or rear stitch forming mechanism. The plate 46 is disposed in rear of the front seam forming mechanism and is provided at its front end with an upturned toe 47. Thus it will be 35 seen that the ridge *d* extends along the line of the initial seam and includes the latter, the upwardly extending inside marginal portions *e* and *f* of the body fabrics being disposed in side-by-side relation and entirely 40 covering or embracing the line of stitches *c* and the trimmed marginal portions *a* and *b*.

The groove 45 is formed in a boss or rib 48 which extends upwardly from the plate 46, and includes spaced vertical walls 49, 50 45 and a top wall 51. The wall 50 and top 51 of the boss 48 are cut away intermediate the front and rear ends, and the remaining or exposed portion of the wall 49 constitutes a vertical needle or guide plate 49^a. A curved 55 needle 52 is fixed to a needle arm 53 which is fulcrumed on the stitching head 7 at a point directly above the ridge *d* whereby the needle reciprocates in a plane transverse to the line of feed and operates entirely above the general plane of the fabrics. The needle 52 passes through the ridge *d* below the trimmed edges of the marginal portions *a* and *b*, and 60 cooperating with the needle to form a line of lock stitches *g* is a rotary hook 54. The needle 52 is actuated from the main shaft 65

13 by connections indicated generally by the numeral 55 and the hook 54 is actuated from the main shaft by connections indicated generally by the numeral 56.

The upper work presenting mechanism includes a vertical 4-motion feed dog 57 which operates through an opening formed in the needle plate 19^a, and a vertical presser foot 58 which cooperates with said needle plate and feed dog to feed the ridge *d* past the 70 needle 52. The feed dog 57 is fixed to a feed bar 59 which is fulcrumed on the horizontal plate 46 by a pin and slot connection 60 whereby the feed dog may be given its back and forth movements, and its lateral movements. These motions are imparted to the feed dog by an eccentric 61 fixed to the lower end of a vertical shaft 62 and cooperating with a correspondingly sized opening formed in the rear end of the feed bar. The shaft 62 is rotated from the main shaft 13 by connections indicated as a whole by the numeral 63.

The presser foot 58 is fixed to a bar 64 which is pivoted as at 65 to the horizontal plate 46, and a spring 66 functions to yieldingly urge the foot against the needle plate 85 49^a and feed dog 57.

From the foregoing, it will be observed that the ridge *d* is formed in the body fabrics immediately after the first line of stitches *c* 95 has been formed; that the ridge includes the previously formed trimmed seam, and that the second or upper line of stitches unites the inner marginal portions *e* and *f* of the fabrics along a line below said trimmed edges whereby the completely formed French seam will 100 be flat and the marginal portions *a* and *b* will not be exposed to view.

In the modification shown in Figure 14, the front needle plate 19^a, in rear of the presser foot 21, is provided with a rearwardly extending U-shaped guide 19^b for receiving the marginal portions *a* and *b*. The guide 19^b extends into the groove 45 of the plate 46 whereby the walls of the groove will cooperate with the guide to form the resultant ridge *d* as will be readily understood.

Having thus described the invention, what is claimed is:

1. In a sewing machine for forming French seams, the combination with complete front and rear stitch forming mechanisms, each mechanism including a reciprocating needle and a cooperating loop taker, one of said complete mechanisms operating entirely below the general plane of the fabrics to be seamed and the other complete mechanism operating entirely above the general plane of said fabrics, and work presenting mechanisms for successively presenting vertical edge portions of fabrics to said stitch forming mechanisms.

2. In a sewing machine for forming French seams, the combination with complete front and rear stitch forming mechanisms,

each mechanism including a reciprocating needle and a cooperating loop taker, one of said complete mechanisms operating entirely below the general plane of the fabrics to be seamed and the other complete mechanism operating entirely above the general plane of said fabrics, and work presenting mechanisms for successively presenting vertical edge portions of fabrics to said stitch forming mechanisms, each work presenting mechanism including a vertical feed dog and a cooperating vertical foot.

3. In a sewing machine for forming French seams, the combination with front and rear stitch forming mechanisms, one of said mechanisms operating entirely below the general plane of the fabrics to be seamed and the other operating entirely above the general plane of said fabrics, and work presenting mechanisms for successively presenting vertical edge portions of fabrics to said stitch forming mechanisms, each work presenting mechanism including a vertical needle plate, a presser foot cooperating with the plate, and a feed dog operating through the plate and cooperating with the foot.

4. In a sewing machine for forming French seams, the combination with complete front and rear stitch forming mechanisms, each mechanism including a reciprocating needle and a cooperating loop taker, one of said complete mechanisms operating entirely below the general plane of the fabrics to be seamed and the other complete mechanism operating entirely above the general plane of said fabrics, work presenting mechanisms for successively presenting vertical edge portions of fabrics to said stitch forming mechanisms, and means located in front of the rear stitch forming mechanism for trimming the edge portions of the fabrics.

5. In a sewing machine for forming French seams, the combination with front and rear stitch forming mechanisms, the former operating entirely below the general plane of the fabrics to be seamed and the latter operating entirely above the general plane of said fabrics, and front and rear work presenting mechanisms for successively presenting downwardly extending marginal fabric portions to the front stitch forming mechanism and upwardly extending seamed marginal fabric portions to the rear stitch forming mechanism.

6. In a sewing machine for forming French seams, the combination with front and rear stitch forming mechanisms, the former operating entirely below the general plane of the fabrics to be seamed and the latter operating entirely above the general plane of said fabrics, and front and rear work presenting mechanisms for successively presenting downwardly extending marginal fabric portions to the front stitch forming mechanism and upwardly extending

seamed marginal fabric portions to the rear stitch forming mechanism, each work presenting mechanism including a vertical feed dog and a cooperating vertical presser foot.

7. In a sewing machine for forming French seams, the combination with front and rear stitch forming mechanisms, the former operating entirely below the general plane of the fabrics to be seamed and the latter operating entirely above the general plane of said fabrics, front and rear work presenting mechanisms for successively presenting downwardly extending marginal fabric portions to the front stitch forming mechanism and upwardly extending seamed marginal fabric portions to the rear stitch forming mechanism, and means located in front of the rear stitch forming mechanism for trimming the edge portions of the fabrics.

8. In a sewing machine for forming French seams, the combination with front and rear stitch forming mechanisms, one of said mechanisms operating entirely below the general plane of the fabrics to be seamed and the other operating entirely above the general plane of said fabrics, a mechanism for presenting vertical edge portions of fabrics to the front stitch forming mechanism, and a mechanism for presenting the seamed edge portions of the fabrics to the rear stitch forming mechanism including means for projecting a ridge of the fabrics including the formed seam into position for seaming by the rear stitch forming mechanism.

9. In a sewing machine for forming French seams, the combination with front and rear stitch forming mechanisms, one of said mechanisms operating entirely below the general plane of the fabrics to be seamed and the other operating entirely above the general plane of said fabrics, a mechanism for presenting vertical edge portions of fabrics to the front stitch forming mechanism, and a mechanism for presenting the seamed edge portions of the fabrics to the rear stitch forming mechanism including a stationary finger for projecting a ridge of the fabrics including the formed seam into position for seaming by the rear stitch forming mechanism.

10. In a sewing machine for forming French seams, the combination with front and rear stitch forming mechanisms, one of said mechanisms operating entirely below the general plane of the fabrics to be seamed and the other operating entirely above the general plane of said fabrics, a mechanism for presenting vertical edge portions of fabrics to the front stitch forming mechanism, means for trimming the vertical edge portions of the fabrics, and a mechanism for presenting the seamed edge portions of the fabrics to the rear stitch forming mechanism including means for projecting a ridge of the fabrics including the formed seam into posi-

tion for seaming by the rear stitch forming mechanism.

11. In a sewing machine for forming French seams, the combination with front and rear stitch forming mechanisms, one of said mechanisms operating entirely below the general plane of the fabrics to be seamed and the other operating entirely above the general plane of said fabrics, a mechanism for presenting vertical edge portions of fabrics to the front stitch forming mechanism, and a mechanism for presenting the seamed edge portions of the fabrics to the rear stitch forming mechanism including means for projecting a ridge of the fabrics including the formed seam into position for seaming by the rear stitch forming mechanism, said work presenting mechanisms each including a vertical presser foot and a cooperating vertical feed dog.

12. In a sewing machine for forming French seams, the combination with front and rear stitch forming mechanisms, one of said mechanisms operating entirely below the general plane of the fabrics to be seamed and the other operating entirely above the general plane of said fabrics, means for directing vertical edge portions of fabrics into position for seaming by the front stitch forming mechanism, and means for projecting a ridge of the fabrics including the formed seam into position for seaming by the rear stitch forming mechanism.

13. In a sewing machine for forming French seams, the combination with front and rear stitch forming mechanisms, one of said mechanisms operating entirely below the general plane of the fabrics to be seamed and the other operating entirely above the general plane of said fabrics, means for directing vertical edge portions of fabrics into position for seaming by the front stitch forming mechanism, a vertical presser foot located at one side of the vertical edge portions of the fabrics, a vertical feed dog located at the other side of said vertical edge portions and cooperating with the foot to feed the fabrics past the front stitch forming mechanism, and means for projecting a ridge of the fabrics including the formed seam into position for seaming by the rear stitch forming mechanism.

14. In a sewing machine for forming French seams, the combination with front and rear stitch forming mechanisms, one of said mechanisms operating entirely below the general plane of the fabrics to be seamed and the other operating entirely above the general plane of said fabrics, means for directing vertical edge portions of fabrics into position for seaming by the front stitch forming mechanism, a trimming mechanism operating in front of the rear stitch forming mechanism for trimming the edge portions of the seamed fabrics, and means located in rear of the trim-

ming mechanism for projecting a ridge of the fabrics including the trimmed seam into position for seaming by the rear stitch forming mechanism with the trimmed edge portions of the first seam within the ridge but out of stitching relation with respect to the second stitch forming mechanism.

15. In a sewing machine for forming French seams, the combination with a complete lower stitch forming mechanism including a needle and a cooperating loop taker and a cooperating work presenting mechanism operating entirely below the general plane of the fabrics being seamed, a complete upper stitch forming mechanism, including a needle and a cooperating loop taker operating entirely above the general plane of the fabrics being seamed, one of said stitch forming mechanisms being located in front of the other, and a work presenting mechanism cooperating with the upper stitch forming mechanism.

16. In a sewing machine for forming French seams, the combination with a complete lower stitch forming mechanism including a needle and a cooperating loop taker and a cooperating work presenting mechanism operating entirely below the general plane of the fabrics being seamed, a complete upper stitch forming mechanism including a needle and a cooperating loop taker operating entirely above the general plane of the fabrics being seamed, one of said stitch forming mechanisms being located in front of the other, a work presenting mechanism cooperating with the upper stitch forming mechanism, and a trimming mechanism operating entirely below the general plane of the body fabrics and in front of the rear stitch forming mechanism.

17. In a sewing machine for forming French seams, the combination with a complete lower stitch forming mechanism and a cooperating work presenting mechanism operating entirely below the general plane of the fabrics being seamed, a complete upper stitch forming mechanism operating entirely above the general plane of the fabrics being seamed, and a work presenting mechanism cooperating with the upper stitch forming mechanism, the upper stitch forming mechanism and the upper work presenting mechanism being disposed in rear of the lower stitch forming mechanism and work presenting mechanism.

18. In a sewing machine for forming French seams, the combination with a complete lower stitch forming mechanism and a cooperating work presenting mechanism operating entirely below the general plane of the fabrics being seamed, a complete upper stitch forming mechanism operating entirely above the general plane of the fabrics being seamed, a work presenting mechanism cooperating with the upper stitch forming mech-

anism, the upper stitch forming mechanism and work presenting mechanism being disposed in rear of the lower stitch forming mechanism and work presenting mechanism, 5 and a trimming mechanism operating entirely below the general plane of the body fabrics and in front of said rear stitch forming mechanisms.

19. In a sewing machine for forming 10 French seams, the combination with front and rear stitch forming mechanisms, the former operating entirely below the general plane of the fabrics to be seamed and the latter operating entirely above the general plane of said fabrics, front and rear work presenting mechanisms for successively presenting downwardly extending marginal fabric portions to the front stitch forming mechanism and upwardly extending seamed marginal fabric portions to the rear stitch forming mechanism, the front work presenting 15 mechanism including a vertical needle plate and a cooperating vertical presser foot, and a trimming mechanism including a horizontally reciprocatory blade located below the needle plate and presser foot and movable 20 across the meeting faces thereof.

20. In a sewing machine for forming 25 French seams, the combination with front and rear stitch forming mechanisms, the former operating entirely below the general 30 plane of the fabrics to be seamed and the latter operating entirely above the general plane of said fabrics, front and rear work presenting mechanisms for successively presenting downwardly extending marginal 35 fabric portions to the front stitch forming mechanism and upwardly extending seamed marginal fabric portions to the rear stitch forming mechanism, the front work presenting 40 mechanism respectively including reciprocatory needles having penetrating movements in the same direction, and means for reciprocating 45 said needles in unison.

21. In a sewing machine, the combination 50 with a frame including a work support and a stitching head located above the support, 55 of a complete stitch forming mechanism including a needle and a cooperating loop taker mounted on the head, and a mechanism mounted on the head for presenting work to the stitch forming mechanism including a vertical presser foot and a cooperating vertical feed dog.

22. In a sewing machine, the combination 60 with a frame including a work support and a stitching head located above the support, 65 of a complete stitch forming mechanism mounted on the head, and a mechanism mounted on the head for presenting work to the stitch forming mechanism including a vertical work guide, a vertical presser foot cooperating therewith, and a vertical feed

dog cooperating with the foot and movable through the work guide.

23. In a sewing machine for forming 70 French seams, the combination with front and rear stitch forming mechanisms, the former operating entirely below the general plane of the fabrics to be seamed and the latter operating entirely above the general plane of said fabrics, front and rear work presenting mechanisms for successively presenting 75 downwardly extending marginal fabric portions to the front stitch forming mechanism and upwardly extending seamed marginal fabric portions to the rear stitch forming mechanism, the front work presenting 80 mechanism including a vertical needle plate and a cooperating vertical presser foot, and a trimming mechanism including a horizontally reciprocatory blade located below the needle plate and presser foot and movable 85 across the meeting faces thereof.

24. In a sewing machine for forming 90 French seams, the combination with front and rear stitch forming mechanisms, the former operating entirely below the general 95 plane of the fabrics to be seamed and the latter operating entirely above the general plane of said fabrics, front and rear work presenting mechanisms for successively presenting downwardly extending marginal fabric portions to the front stitch forming mechanism and upwardly extending seamed marginal fabric portions to the rear stitch forming mechanism, the front work presenting 100 mechanism including a vertical needle plate and a cooperating vertical presser foot, and a trimming mechanism including a horizontally reciprocatory blade located below the needle plate and presser foot and movable 105 across the meeting faces thereof and cooperating with a lower edge of the vertical needle plate.

25. In a sewing machine for forming 110 French seams, the combination with front and rear stitch forming mechanisms, the former operating entirely below the general 115 plane of the fabrics to be seamed and the latter operating entirely above the general plane of said fabrics, front and rear work presenting mechanisms for successively presenting downwardly extending marginal fabric portions to the front stitch forming mechanism and upwardly extending seamed marginal fabric portions to the rear stitch forming mechanism, the front work presenting 120 mechanism including a vertical needle plate and a cooperating vertical presser foot, and a trimming mechanism including a vertically disposed rock shaft, a horizontally reciprocatory blade fixed to said shaft and located below the needle plate and presser foot and movable across the meeting faces thereof.

26. In a sewing machine for forming 125 French seams, the combination with front and rear stitch forming mechanisms, the 130

former operating entirely below the general plane of the fabrics to be seamed and the latter operating entirely above the general plane of said fabrics, and front and rear work presenting mechanisms for successively presenting downwardly extending marginal fabric portions to the front stitch forming mechanism and upwardly extending seamed marginal fabric portions to the rear stitch forming mechanism, the front work presenting mechanism including a vertical needle plate, a vertical presser foot cooperating with the plate, a vertical 4-motion feed dog operating through the plate and cooperating with the foot, and means for automatically moving the foot away from the plate during feeding movements of the feed dog.

27. In a sewing machine for forming French seams, the combination with front and rear stitch forming mechanisms, the former operating entirely below the general plane of the fabrics to be seamed and the latter operating entirely above the general plane of said fabrics, and front and rear work presenting mechanisms for successively presenting downwardly extending marginal fabric portions to the front stitch forming mechanism and upwardly extending seamed marginal fabric portions to the rear stitch forming mechanism, the front work presenting mechanism including a vertical needle plate, a vertical presser foot cooperating with the plate, a vertical 4-motion feed dog operating through the plate and cooperating with the foot, a spring for normally retaining the foot in engagement with the plate, and means for automatically moving the foot away from the plate and against the tension of the spring during feeding movements of the feed dog.

28. In a sewing machine for forming French seams, the combination with front and rear stitch forming mechanisms, the former operating entirely below the general plane of the fabrics to be seamed and the latter operating entirely above the general plane of said fabrics, and front and rear work presenting mechanisms for successively presenting downwardly extending marginal fabric portions to the front stitch forming mechanism and upwardly extending seamed marginal fabric portions to the rear stitch forming mechanism, the front work presenting mechanism including a vertical needle plate, a horizontally disposed presser bar, a vertical presser foot slidably mounted on said bar, and a coil spring around the bar for yieldably retaining the foot against the plate.

29. In a sewing machine for forming French seams, the combination with front and rear stitch forming mechanisms, the former operating entirely below the general plane of the fabrics to be seamed and the latter operating entirely above the general plane of said fabrics, and front and rear work presenting mechanisms for successively presenting

downwardly extending marginal fabric portions to the front stitch forming mechanism and upwardly extending seamed marginal fabric portions to the rear stitch forming mechanism, the front work presenting mechanism including a vertical needle plate, a horizontally disposed presser bar, a vertical presser foot slidably mounted on said bar, a sleeve slidable on the bar, a collar fixed to the bar, a vertical presser foot fixed to the sleeve, and a coil spring interposed between the foot and the collar for yieldably retaining the foot against the plate.

30. In a sewing machine for forming French seams, the combination with front and rear stitch forming mechanisms, the former operating entirely below the general plane of the fabrics to be seamed and the latter operating entirely above the general plane of said fabrics, and front and rear work presenting mechanisms for successively presenting downwardly extending marginal fabric portions to the front stitch forming mechanism and upwardly extending seamed marginal fabric portions to the rear stitch forming mechanism, the front work presenting mechanism including a vertical needle plate, a horizontally disposed presser bar, a vertical presser foot slidably mounted on said bar, a sleeve slidable on the bar, a collar fixed to the bar, a vertical presser foot fixed to the sleeve, a coil spring interposed between the foot and the collar for yieldably retaining the foot against the plate, and a guide bar disposed in parallelism with the presser bar and having rigid connection with the foot and having slidable connection with the collar.

31. In a sewing machine for forming French seams, the combination with a front stitch forming mechanism operating entirely below the general plane of the fabrics to be seamed, a work presenting mechanism including a vertical feed dog for presenting downturned edge portions of the fabrics to said front stitch forming mechanism, a rear stitch forming mechanism operating entirely above the general plane of the fabrics, and a work presenting mechanism for feeding the seamed edge portions of the fabrics to said rear stitch forming mechanism including a vertical feed dog disposed in rear of and in alignment with the front feed dog and located above the general plane of the fabrics, and means for projecting upwardly a ridge of the fabrics including the formed seam into position for seaming by the rear stitch forming mechanism.

32. In a sewing machine for forming French seams, the combination with a front stitch forming mechanism operating entirely below the general plane of the fabrics to be seamed, a work presenting mechanism including a vertical feed dog for presenting downturned edge portions of the fabrics to

said front stitch forming mechanism, a rear stitch forming mechanism operating entirely above the general plane of the fabrics, and a work presenting mechanism for feeding the seamed edge portions of the fabrics to said rear stitch forming mechanism including a vertical feed dog disposed in rear of and in alinement with the front feed dog and located above the general plane of the fabrics, and 10 means for projecting upwardly a ridge of the fabrics including the formed seam into position for seaming by the rear stitch forming mechanism, said stitch forming mechanisms including reciprocatory needles having 15 their paths of movements in planes transverse to the line of feed of the fabrics.

33. In a sewing machine for forming French seams, the combination with a front stitch forming mechanism operating entirely 20 below the general plane of the fabrics to be seamed, a work presenting mechanism including a vertical feed dog for presenting downturned edge portions of the fabrics to said front stitch forming mechanism, a rear 25 stitch forming mechanism operating entirely above the general plane of the fabrics, and a work presenting mechanism for feeding the seamed edge portions of the fabrics to said rear stitch forming mechanism including a vertical feed dog disposed in rear of and in alinement with the front feed dog and located 30 above the general plane of the fabrics, and means for projecting upwardly a ridge of the fabrics including the formed seam into 35 position for seaming by the rear stitch forming mechanism, said stitch forming mechanisms including reciprocatory needles having their paths of movements in planes transverse to the line of feed of the fabrics, the front 40 needle having a straight line movement and the rear needle being mounted for oscillations about an axis located directly above but in rear of the ridge forming means.

34. In a sewing machine for forming 45 French seams, the combination with a front stitch forming mechanism operating entirely below the general plane of the fabrics to be seamed, a work presenting mechanism including a vertical feed dog for presenting 50 downturned edge portions of the fabrics to said front stitch forming mechanism, a rear stitch forming mechanism operating entirely above the general plane of the fabrics, and a work presenting mechanism for feeding the 55 seamed edge portions of the fabrics to said rear stitch forming mechanism including a vertical feed dog disposed in rear of and in alinement with the front feed dog and located 60 above the general plane of the fabrics, and means for projecting upwardly a ridge of the fabrics including the formed seam into position for seaming by the rear stitch forming mechanism, said stitch forming mechanisms including reciprocatory needles 65 having their paths of movements in planes

transverse to the line of feed of the fabrics, and having their penetrating movements in the same direction, and means for reciprocating said needles in unison.

35. In a sewing machine for forming French seams, the combination with a front 70 stitch forming mechanism operating entirely below the general plane of the fabrics to be seamed and including a reciprocatory needle and a cooperating 4-motion threaded looper, a work presenting mechanism including a vertical feed dog for presenting downturned edge portions of the fabrics to said front stitch forming mechanism, a rear stitch forming mechanism operating entirely above the general plane of the fabrics, and a work 75 presenting mechanism for feeding the seamed edge portions of the fabrics to said rear stitch forming mechanism including a vertical feed dog disposed in rear of and in alinement with the front feed dog and located 80 above the general plane of the fabrics, and means for projecting upwardly a ridge of the fabrics including the forward seam into 85 position for seaming by the rear stitch forming mechanism.

36. In a sewing machine for forming French seams, the combination with a front stitch forming mechanism operating entirely below the general plane of the fabrics to be seamed, a work presenting mechanism including a vertical feed dog for presenting downturned edge portions of the fabrics to said front stitch forming mechanism, a rear stitch forming mechanism operating entirely above the general plane of the fabrics, and a work 90 presenting mechanism for feeding the seamed edge portions of the fabrics to said rear stitch forming mechanism including a vertical feed dog disposed in rear of and in alinement with the front feed dog and located above the general plane of the fabrics, and a stationary finger located between the front and rear feed dogs and projecting upwardly from a point 95 below the general plane of the fabrics to a point above a horizontal plane containing the point of penetration of the rear needle for projecting a ridge of the fabrics including the formed seam into position for seaming by the rear stitch forming mechanism.

37. In a sewing machine for forming French seams, the combination with a front stitch forming mechanism operating entirely below the general plane of the fabrics to be seamed, a work presenting mechanism including a vertical feed dog for presenting downturned edge portions of the fabrics to said front stitch forming mechanism, a rear stitch forming mechanism operating entirely above the general plane of the fabrics, and a work presenting mechanism for feeding the seamed edge portions of the fabrics to said rear stitch forming mechanism including a vertical feed dog disposed in rear of and in alinement with the front feed dog and lo-

cated above the general plane of the fabrics, a stationary finger located between the front and rear feed dogs and projecting upwardly from a point below the general plane of the fabrics to a point above a horizontal plane containing the point of penetration of the rear needle for projecting a ridge of the fabrics including the formed seam into position for seaming by the rear stitch forming mechanism, and means on opposite sides of the finger for holding the fabrics against upward movement during the formation of the ridge by the finger.

38. In a sewing machine for forming French seams, the combination with a front stitch forming mechanism operating entirely below the general plane of the fabrics to be seamed, a work presenting mechanism including a vertical feed dog for presenting downturned edge portions of the fabrics to said front stitch forming mechanism, a rear stitch forming mechanism operating entirely above the general plane of the fabrics, and a work presenting mechanism for feeding the seamed edge portions of the fabrics to said rear stitch forming mechanism including a vertical feed dog disposed in rear of and in alinement with the front feed dog and located above the general plane of the fabrics, a stationary finger located between the front and rear feed dogs and projecting upwardly from a point below the general plane of the fabrics to a point above a horizontal plane containing the point of penetration of the rear needle for projecting a ridge of the fabrics including the formed seam into position for seaming by the rear stitch forming mechanism, and a stationary plate having a channel in its under side for receiving the upper end of the ridge forming finger and cooperating with said finger to hold the fabrics against upward movement during formation of the ridge by the finger.

39. In a sewing machine, the combination with a vertical guide plate, of a laterally movable presser foot cooperating therewith, a spring for normally holding the foot yieldingly in engagement with the plate, a vertically disposed rock shaft, a horizontal trimmer blade fixed to the shaft for cooperation with the lower edge of the guide plate, means for rocking said shaft to oscillate the trimmer blade, and means actuated by the shaft for moving the foot away from the guide plate simultaneously with the retractile movement of the trimmer blade.

40. In a sewing machine, the combination of a vertical needle plate and a cooperating presser foot, and a trimming mechanism including a horizontally reciprocatory blade located below the needle plate and presser foot and movable across the meeting faces thereof.

41. In a sewing machine, the combination of a vertical needle plate and a cooperating

presser foot, and a trimming mechanism including a horizontally reciprocatory blade located below the needle plate and presser foot and movable across the meeting faces thereof, and cooperating with a lower edge of the vertical needle plate.

42. In a sewing machine, the combination of a vertical needle plate and a cooperating presser foot, a trimming mechanism including a vertically disposed rock shaft, a horizontally reciprocatory blade fixed to said shaft and located below the needle plate and presser foot and movable across the meeting faces thereof, and means for oscillating said shaft.

43. In a sewing machine, the combination with a vertical needle plate, a vertical presser foot cooperating with said plate, a vertical 4-motion feed dog operating through the plate and cooperating with the foot, and means for automatically moving the foot away from the plate during feeding movements of the feed dog.

44. In a sewing machine, the combination with a vertical needle plate, a vertical presser foot cooperating with said plate, a vertical 4-motion feed dog operating through the plate and cooperating with the foot, a spring for normally retaining the foot in engagement with the plate, and means for automatically moving the foot away from the plate and against the tension of the spring during feeding movements of the feed dog.

45. In a sewing machine, the combination with a vertical needle plate, of a horizontally disposed presser bar, a sleeve slidable on the bar, a collar fixed to the bar, a vertical presser foot fixed to the sleeve, and a coil spring interposed between the foot and the collar for yieldably retaining the foot against the plate.

46. In a sewing machine, the combination with a vertical needle plate, of a horizontally disposed presser bar, a sleeve slidable on the bar, a collar fixed to the bar, a vertical presser foot fixed to the sleeve, a coil spring interposed between the foot and the collar for yieldably retaining the foot against the plate, and a guide bar disposed in parallelism with the presser bar and having rigid connection with the foot and having slidable connection with the collar.

In testimony whereof I affix my signature this 12th day of October, 1927.

HORACE F. GRUMAN. 120
